(57) CLAIM

The ornamental design for a display screen with graphical user interface, as shown and described.

DESCRIPTION

The sole FIGURE is a front view of a display screen with graphical user interface showing the new design.

The dot-dash lines in the figure illustrate the bounds of the claim. The dash-dash broken line showing of a display device illustrates environment. The remaining broken lines illustrate portions of the display screen with graphical user interface. The broken lines form no part of the claimed design.

1 Claim, 1 Drawing Sheet
